AUTOMATIC AIR ENVELOPE KNOCKOUT

Edmund E. Moore, Brooklyn, N. Y.

Application March 14, 1936, Serial No. 68,797

14 Claims. (Cl. 93—72)

This invention relates to envelope manufacturing machinery, being concerned particularly with means for releasing and driving a completed envelope from the machine to a suitable receiving conveyor. The invention is particularly adapted for use on envelope machinery adapted for the production of so-called "window envelopes," wherein a transparent glassine window patch is pasted over a window cut-out in the face of the envelope.

Briefly summarizing the development of these machines, the solid envelope was first made; then later came the window envelope having no glassine patch—simply a cut-out in the face of the envelope. Then, a transparent patch was pasted over the window, the patch being secured to the envelope by a thin line of gum adhesive all around the patch; it was necessary to keep the line of gum away from the edge of the patch in order that the paste would not ooze out to possibly stick the front and rear faces of the envelope together. In this design, the loose edge of the patch often caused trouble by catching inserted matter, particularly when automatic envelope filling machines were used. To obtain a practical, smooth patch securely adhered to the envelope throughout its edge, the heat-sealing patch was developed. Glassine or transparent paper, specially chemically treated on one side with a nitro-cellulose compound, is stuck to the envelope by the application of heat and pressure with a predetermined dwell and subsequent cooling. This process is accomplished by a hot plunger which moves up and down on the envelope machine and presses upon the heat-sealing patch. In the ordinary envelope machine, a trap or table is provided upon which the envelope is fed and processed, whereupon the trap is quickly inclined downwardly at a sharp angle and fingers come up through slots in the trap to engage an edge of the envelope to drive the envelope downwardly onto a conveyor. When envelopes are made with heat-sealing patches, the slots in the trap through which the fingers project, interfere with proper processing, and likewise the fingers scar the edge of the envelope. If slots were used in the heat-sealing envelope machine, it would be necessary to also slot the pad upon which the envelope rests when the hot plunger is applied, resulting in incomplete adhesion of the patch to the envelope. It therefore becomes necessary to devise a new method of knocking out the completed heat-sealed envelopes, although the apparatus comprising this

new improvement is adapted for use with any type of envelope.

My invention, then, comprises a new means for quickly and positively removing envelopes from one position to another in the envelope machine. For accomplishing this end, I utilize pneumatic apparatus which presents additional advantages when used on machines producing heat-sealed patch window envelopes. As above indicated, the 10 heat-sealing process involves heat, pressure, dwell and cooling. By utilizing a pneumatic knock-cut device, the compressed air fulfills the last function of cooling of the completed envelope.

15 Objects of the invention, in addition to those inferred above, will be apparent in reading the annexed specification and in examining the drawings, in which:

Fig. 1 is a side elevation, partly in section, showing the table and trap of an envelope machine embodying the improvements of this invention;

Fig. 2 is a view similar to Fig. 1 showing the apparatus in a different position of operation;

Fig. 3 is a view on the line 3—3 of Fig. 1;

Fig. 4 is a view similar to Fig. 2, showing in addition, the pneumatic apparatus and timing means therefor;

Fig. 5 is an enlarged section of part of the apparatus shown in previous figures;

Fig. 6 shows an alternative organization of the envelope knock-out improvements;

Figs. 7 and 8 are plans of parts of the apparatus;

Fig. 9 is a side elevation of an adjustable arrangement for the air knock-out apparatus;

Fig. 10 is a plan of the adjustable apparatus of Fig. 9;

Fig. 11 is an end elevation of the apparatus of Fig. 9; and

Fig. 12 shows an alternative trap organization provided with means for liquid cooling.

Referring to Figs. 1 to 5, I show the conventional work table 15 of an envelope machine, this table having a cut-out 16 within which a trap 17 is carried on a pivot 18 for swinging between the positions shown in Fig. 1 in solid and dotted lines, respectively. This trap is moved up and down by means of a rod 19 hinged thereto, the bottom end of the rod operating against a cam 20 in the conventional manner. The trap 17 is provided with a work pad 21 upon which a resilient pad 22 is fixed, said resilient pad being of an outline corresponding to the shape of the window cut-out in the envelope 23 adapt-

ed to be operated upon. The machine carries a plunger 24 having a head 25 adapted to bear down upon the envelope 23, the head 25 being heated and being operated in timed relation, so that, when the trap carries an envelope in its uppermost position, said head bears upon the envelope to heat-seal the transparent patch to the envelope. The operating mechanism for the plunger 24 is not shown in detail as this is old in the art and forms no part of the present invention. After the heat-sealing operation has been completed, the plunger rises from the trap and the cam 20 rotates to permit the trap to swing down upon its pivot 18, whereby the envelope 23 may be discharged onto a conveyor belt 26.

To expedite discharge of the envelope from the trap after the latter has been lowered, I provide a plunger and pneumatic jet organization indicated as 27, this organization being carried by the trap. The pad 21 is provided with an opening 28 through which a pin 29 carried on the plunger organization 27 is adapted to rise, the pin 29 being carried by a cross yoke 30 slidably in a direction normal to the face of the pad 21; a guide 31 is fixed to the trap 17, and a rod 32 attached to the yoke 30 engages the guide. The bottom end of the rod 32 carries a roller 33 adapted to engage a cam 34 carried by the table 15. When the trap 17 drops down, the roller 33 engages the cam 34, forcing the pin 29 up through the pad 21 to raise the envelope from the pad 22. The yoke 30 also carries an upstanding tube 35 having an orifice 36 directed toward the envelope, said tube 35 being arranged to elevate above the level of the pads 21 and 22.

Means are provided, as shown in Fig. 4, to furnish air under pressure to the orifice 36 in properly timed relationship, so that when the tube 35 is raised above the pad, an airstream is directed toward the edge of the envelope 23 by which the envelope is blown from the trap to drop by gravity onto the conveyor 26. This jet action, indicated in Fig. 2, is very effective in quickly driving the envelope from the trap, since that air which passes below the entering edge of the envelope tends to cushion the envelope and at the same time cool it. That air which passes above the edge of the envelope impinges upon the acutely angled flap 37 to expedite ejection. The ejection of the envelope is also expedited by virtue of the airfoil action of the envelope, since the envelope has been tilted upwardly at its entering edge by means of the pin 29, whereby the envelope has a positive angle of attack with respect to the jet stream. Thereby, a slight suction is induced on the upper surface of the envelope, while pressure is induced on the lower side thereof, aiding in raising the envelope from the trap whereby it floats on the airstream from the trap and toward the conveyor. A baffle 38 may be screwed to the bottom of the table 15 to deflect the envelope directly toward the conveyor after the envelope has left the trap.

The tube 35 is provided with a nipple 39 over the end of which a flexible hose 40 is slipped, said flexible hose, shown in Fig. 4, passing over a sheave 41 to a valve housing 42 fixed to the machine. Said valve housing includes a spring-pressed poppet valve 43, the stem of which extends below the housing 42 for engagement with a valve lifter 44 engageable with a cam 45 suitably driven from the power source of the machine. The valve timing is so coordinated with the operation of the machine that the valve is

open at that instant when the orifice 36 rises above the pad of the trap 17, the valve staying open during the period that the trap is in its lower position, and the valve closing at such time as the trap is raised to operating position simultaneously with the dropping of the orifice 36 below the level of the pad. The valve housing 42 is continually supplied with air under pressure from a power driven compressor 46 through a balance and sediment chamber 47. In Fig. 4, I show a humidifier and temperature controller 48 connectible in the air circuit from the compressor 46 by means of selectively operable valves 49 and 50. When said valves are open, another valve 51 leading from the compressor 46 directly to the chamber 47, is closed, whereby the compressed air is diverted through the humidifier and temperature controller before reaching the chamber 47. If it is not necessary to humidify, heat or cool the air, the valves 49 and 50 are closed, and the valve 51 opened, by which compressed air passes directly from the compressor 46 to the chamber 47.

Special reference may be made to Fig. 5, wherein the details of construction of the plunger organization 27 are shown. It will be here noted that the rod 32 is counter-bored as at 53 to receive a spring 54, the upper end of which spring is guided by a pin 55 screwed into the lower part of the pad 21. Thus, the spring 54 continually urges the pin 29 and tube 35 to a low position, against the action of the cam 34 which serves to raise same upon dropping of the trap. Figs. 1 and 2 show the detailed organization of the cam 34 which comprises an arm pivoted at 57 to a bracket 58 screwed to the table 15. Said bracket 58 also carries a member 59 against which an adjusting screw 60 in the cam bar 34 may bear to predetermine the uppermost position of the cam bar. A screw 61 is arranged to pass freely through the cam bar 34, to be threaded into the member 59, and a spring 62 bears at its ends against the head of the screw 61 and against the cam bar 34 to continually urge the cam bar toward its uppermost position. Thus, the cam bar is resiliently mounted and is adjustable so that the extent of elevation of the pin 29 and the tube 35 above the trap may be preset according to the character of envelopes upon which the machine is operating. Additionally, the plunger organization 27 and the cam 34 with its associated mounting elements are so arranged that they may easily be attached to existing types of envelope machines without the necessity for expensive redesign or rebuilding of the machines.

In Figs. 6 to 11, inclusive, I show a modification of the plunger organization 27 and of the means for carrying the cam 34, which provide for a greater universality of adjustment to accommodate the apparatus to variant shapes and sizes of envelopes. In these figures, 65 represents a cross plate screwed at its ends to the flanges on the bottom of the trap 15. Said plate is provided with a central slot 66 and adjacent bolt holes 67. A yoke 68, shown in plan in Fig. 7, is provided with an opening 69 and adjacent slots 70, the slots 70 registering with the holes 67, through which slots and holes, bolts 71 are passed to firmly attach the yoke 68 to the plate 65. The opening 69 in the yoke 68 receives a rod 32' carrying a yoke 30' upon which are mounted a pin 29' and an air tube 35'. The yoke 68 is extended upwardly to provide guideways at 72 and 73, respectively, for the pin 29' and the tube

35'. A guide pin 55' is fixed to the upper end of the yoke 68 to engage a suitable opening in the yoke 38', and springs 74 and 75 between the upper end of the yoke 68 and the yoke 38', and respectively embracing the pins 29' and 55', serve to urge the yoke 38' downwardly with respect to the trap 15. In this arrangement, the pin 29' and jet tube 35' may be adjusted toward or away from the trap pivot 18 as a unit, the trap pad 21' being interchangeable with several different sizes to accommodate the machine for work on envelopes of different sizes. In changing from one size envelope to another, it is unnecessary to remove the pneumatic ejecting organization but rather, it is only necessary to adjust it to the 15 character of work contemplated.

To coordinate the cam 34 with the adjustable ejecting organization, I show, in Figs. 9, 10 and 11, that the member 59 is bolted, as before, to a bracket 58'. However, said bracket may be adjusted with respect to the table 15 by means of cap screws 80 which may be screwed a greater or lesser distance into the table 15. A set screw 81 serves as a stop to hold the bracket 58' in the proper position relative to the table 15 when 25 the cap screws 80 are tightened.

In Fig. 6, I show an adjusting screw 32 threaded into the upper arm of the yoke 68, which screw serves as a stop to limit the upward motion of the yoke 38' when the latter is raised by means 30 of the cam 34. When said yoke addresses the screw 32, the reaction will cause the rod 32' to bear down upon the cam 34 to deflect the spring 62, as indicated in the structure of Fig. 2.

In Fig. 12, I show a trap 15' of the same general character as is used in the previously shown embodiments, wherein said trap is provided with cored interior openings through which a fluid coolant may be passed. An entrance passage 90 and an exit passage 91 are provided in the organization to connect with flexible hoses 92 and 93, respectively, in turn connected to suitable fluid circulating means. This fluid cooling organization for the trap is desirable in those types of envelope machines which are set up for heat-sealing patches, since the plunger head 25, shown in Fig. 1, is maintained at a constantly relatively high temperature in order to effect the heat-sealing. Upon protracted operation of the machine, a considerable amount of this heat is transmitted to the trap, which may have the effect of sticking the envelope to the trap. By keeping the trap cool, quicker release of the envelope therefrom may be effected to increase the production rate of the machine.

While I have described my invention as applied to changing the position of paper in an envelope machine, there are many other applications where it can be used to change the place of objects either on stationary groups or moving parts. Especially advantageous is the ease of installation and flexibility of control and adjustment for different sizes and the wide range of places where such an automatically raised air discharge tube can be employed.

Although I have described my invention as using a discharged column of air to accomplish certain results, there will be times when the pump can be used as a suction pump and the air line system as a suction system. In this case the air vent tube would become an air suction port and would perform desirable useful work in moving objects from one place to another by a reverse movement of the air flow. The suction port can be differently located as desired or can

be a plurality of apertures. To approach nearer the object to be moved, or in fact to touch the object whose position is to be changed, the air ports or orifices can be of any shape desired for efficient working and have a plurality of holes as required.

It may also be stated that the temperature and humidity of the air stream is also an important factor. It is the pressure or the moving air that is required to change the position of the envelope; but the cold or hot air flow or the humidity of the air blast will in addition facilitate and increase the rapidity of the patch adhesion and delivery.

However, it is not necessary that this air stream be emitted at room temperature. It might be desirable and is so provided to raise or lower the temperature of the air discharge above or below room temperature by the air conditioning and humidity control apparatus as stated, in order to accomplish certain desirable work and to more effectively stick the patch, and at the same time it might be required to lower the temperature of the air blast below that of room temperature or below that of the object at which it is directed.

Means for raising or lowering the temperature of the air stream are not new and apparatus for so doing is not shown in detail in the drawings. Numerous methods are available for raising the temperature and for air conditioning and humidity control of the air stream, and it is not necessary to elaborate on them here. Apparatus of this type would be inserted in or about the air pressure lines so as to increase or decrease the temperature and humidity of the air flow as desired.

In making envelopes and printing, it is found that the paper is very sensitive to the humidity or water content of the air. While my invention shows an air discharge stream at room temperature, there might be applications where the localized humidity about a certain object at a set time in a machine could be increased by inserting in the air line certain standard air conditioning apparatus that would permit the discharge of an air blast of a certain desired humidity. This is a big advantage as it would assure constant "weather" conditions with uniform results from machine operation that would otherwise be influenced by normal weather changes. This is a particularly troublesome factor in the paper manufacturing business, as humidity and temperature changes interfere with rapid production to 55 a marked extent.

I have shown in Fig. 4 an air pump and motor as means of producing air pressure or air suction. This is a handy method, as each machine can conveniently encase the small motor and pump to make a complete operating assembly. But this method is not fixed and the air pressure and air suction can be obtained many other ways, whichever may be most advantageous under the conditions that present themselves. 60 Some shops have central air pressure tanks with air lines running throughout the shop, and the same applies to vacuum or suction tanks.

This invention may be arranged to accomplish certain other ends in processing of paper products. For instance, plural jets may be arranged with one or more jets ejecting air in one state of humidity or temperature, and other jets issuing air under different temperature and humidity conditions. The jet may also be used for applying specialized fluids, or moisture, before

processing of the paper to condition the paper for the ensuing process. For instance, hard surfaced papers may be moistened before processing to soften the surface by which adhesion will be improved, and by which the paper sizing will be affected to expedite the contemplated processing. I therefore include steam and gases for use as alternative fluids for issuance from the jets previously described.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

What is claimed is:

1. An envelope knock-out for the trap of an envelope machine, said trap being hinged for downward swinging to discharge the envelope to a receiver, comprising a plunger in said trap movable in timed relation to downward trap movement to free the envelope from the trap, an air jet nozzle carried by said trap and movable with said plunger, and means for supplying compressed air to said nozzle for issuance therefrom in timed relation to downward trap movement to blow the envelope on said trap, toward said receiver.

2. In an envelope machine having a downwardly swinging, envelope-discharging trap, plunger means movable to raise the envelope from the trap, air jet means operable to blow the envelope from the trap upon downward movement of the latter, said air jet means comprising a nozzle movable with and with respect to the trap, and means for moving the nozzle in timed relation with respect to the trap.

3. In an envelope-discharging mechanism for the downwardly swingable trap of an envelope machine, said trap having an opening therethrough, a guide on the under surface of the trap, a yoke movable in said guide in a direction substantially normal to the top of said trap, a plunger carried by said yoke, extending through said trap opening, an air nozzle on said yoke adapted to extend at times above the top of said trap, a cam on said envelope machine, and a cam follower on said yoke engaged with said cam, said cam being so formed as to raise said yoke with respect to said trap upon downward swinging of said trap.

4. In an envelope-discharging mechanism for the downwardly swingable trap of an envelope machine, said trap having an opening therethrough, a guide on the under surface of the trap, a yoke movable in said guide in a direction substantially normal to the top of said trap, a plunger carried by said yoke, extending through said trap opening, an air nozzle on said yoke adapted to extend at times above the top of said trap, a cam on said envelope machine, a cam follower on said yoke engaged with said cam, said cam being so formed as to raise said yoke with respect to said trap upon downward swinging of said trap, and means for supplying compressed air to said nozzle upon elevation of said nozzle above the upper trap surface.

5. In an envelope machine trap for envelopes having heat-sealed window patches, a ring of resilient material on said trap surface against which a heated plunger is adapted to press the patch border, means for lowering said trap for envelope discharge, means for raising the envelope from said trap, and pneumatic means for

blowing the envelope from said trap after said raising means has become effective.

6. In a fabricating machine for paper products having a movable work station from which products are organized to be periodically discharged, an air nozzle directed toward and movable with said station, means for feeding compressed air to said nozzle in timed relationship to the work accomplished on the product to move said product from said station, and means to move the nozzle relative to the work station in timed relationship to the work accomplished.

7. In a heat-sealing envelope machine wherein sealing of envelope elements is accomplished by the application of heat and pressure, said machine having a station, including a movable discharge trap, at which said sealing is effected, means for loosening the envelope from said trap, means for cooling said envelope and for driving same from said trap comprising a nozzle directed toward said station, and means for valving cool compressed air to said nozzle upon cessation of the sealing operation.

8. The combination, in an envelope machine of a trap movable to discharge an envelope thereon, said trap being organized for envelopes of various size, loosening and discharge means carried by said trap to discharge an envelope therefrom, and means for positioning the loosening and discharge means at various positions on said trap for accommodating envelopes of various size, said loosening and discharge means comprising a loosening plunger and a discharge jet raisable in timed relation above said trap and means to supply compressed air to said jet upon raising thereof, to discharge said envelope from the trap.

9. The combination, in an envelope machine of a trap movable to discharge an envelope thereon, said trap being organized for envelopes of various size, loosening and discharge means carried by said trap to discharge an envelope therefrom, means for positioning the loosening and discharge means at various positions on said trap for accommodating envelopes of various size, said loosening and discharge means comprising a loosening plunger and a discharge jet raisable in timed relation above said trap and means to supply compressed air to said jet upon raising thereof, to discharge said envelope from the trap, and, in combination, means for controlling the pressure, temperature and humidity of the air.

10. In an envelope machine comprising a table and a trap hinged thereto for timed downward movement in response to machine operation, a plunger carried by and slidable relative to said trap in a direction substantially normal to the trap surface, a cam follower on said plunger, below said trap, and a cam bar carried by and below said table with which said cam follower is engaged, said cam being so formed as to slide said plunger relative to said trap upon lowering of said trap.

11. In an envelope discharging mechanism including a swingable trap, a plunger raisable relative to the trap face for raising a portion of an envelope therefrom, a nozzle raisable in timed relationship to trap movement, located close to said plunger, and means to supply said nozzle with compressed air for discharging an envelope on said trap, said raised envelope portion receiving the compressed air for floating the whole envelope from the trap.

12. In an envelope discharging mechanism, having a plate upon which an envelope is adapted to lie flat, a plunger raisable to lift an edge of the

envelope from the plate, a nozzle having a jet directed toward the envelope edge, means to move said nozzle in timed relation with said plunger above the plate, and means to supply said jet with gas in timed relation to the raising of the envelope edge, said gas, upon ejection thereof from the jet, serving to float the envelope from said plate.

13. In an envelope machine including a plate upon which an envelope is adapted to be processed, a resilient pad on said plate upon which an envelope in process rests, a plunger engageable with the envelope to press the envelope against said pad, and means operable upon disengagement of the plunger from the envelope for discharging said envelope from said pad and plate, said means comprising a plunger for raising an edge of the envelope and compressed air

ejecting mechanism operable to float the envelope from the plate.

14. In an envelope discharging mechanism, a plate upon which an envelope is adapted to lie flat, a plunger raisable to lift an edge of the envelope from the plate, a nozzle having a jet directed toward the envelope edge, means to move said plunger and nozzle together in timed relation above the plate, and means for supplying gas at full pressure to said nozzle for passage through said jet throughout the time that the edge of an envelope is lifted by said plunger, said gas upon ejection thereof from the jet serving to induce aerodynamic lift and drag forces on both the upper and lower surfaces of the envelope for floating the envelope from said plate.

EDMUND B. MOORE.
